UNITED STATES PATENT OFFICE.

NEMPHI W. CLAYTON, OF SALT LAKE CITY, UTAH.

LIQUID-VENDING APPARATUS.

Application filed August 17, 1926. Serial No. 129,798.

This invention relates to improvements in liquid vending apparatus, and it consists of the constructions, combinations and arrangements herein described and claimed.

5 An object of the invention is to provide an apparatus primarily intended for vending gasoline, although it is adaptable to dispensing oil, water or other liquid, there being the provision of a glass or other container into which the purchaser can pump the liquid as a preliminary step in the cycle of operation, a further requirement being the insertion of an appropriate coin before the liquid can be released.

10 15 Other objects and advantages will appear in the following specification, reference being had to the accompanying drawings, in which

Figure 1 is a perspective view illustrating the general external appearance of the apparatus,

20 Figure 2 is a central vertical section, parts being in elevation, illustrating the normal position of the parts.

25 Figure 3 is a detail sectional view of the discharge and inlet valves, showing the positions that they normally assume,

30 Figure 4 is a view similar to Figure 2, illustrating the disposal of the parts prior to the dispensation of the liquid from the glass container,

35 Figure 5 is a detail sectional view illustrating the adjustment of the liquid level tube,

Figure 6 is a view similar to Figure 2, illustrating the disposal of the parts during the liquid dispensing operation,

40 Figure 7 is a sectional view of the discharge and inlet valves in the foregoing position,

Figure 8 is a detail view of the coin receiver taken substantially on the line 8-8 of Figure 1.

45 A complete cycle comprises five distinct operations and in order that there may be agreement of said operations with the manually actuated mechanism of the apparatus, the parts involved are numbered in the sequence of said operations as follows: the initiating plunger 1, the pump handle 2, coin plunger 3, (Figs. 1 and 8), main plunger 4 and valve plunger 5.

50 Each of the foregoing parts is located on the outside of the combined standard and casing 6 which both houses the mechanism

and supports the glass container 7 in which the gasoline is visible. It is herein assumed that the apparatus dispenses gasoline, but as already indicated, it is adaptable to the dispensation of other liquids.

60 The glass container 7 is suitably mounted upon the top 8 of the casing (Fig. 5) upon which top it is cemented in place at 9 in circular groove 10. A gasoline inlet pipe 11 leads from the pump casing 12 to the container 7, there being an interposed three-way valve 13 as shown for example in Figures 2 and 3. This valve is normally in position to place the container 7 and pump casing 12 in communication.

65 The pump casing 12 has a supply pipe 14 which leads to an underground storage tank (not shown). A pipe 15 serves as a common tank return both to the container 7 and to the pump casing 12. For the first purpose the tube 16 extends from the upper end of the pipe into the container in reference to which its positions are adjustable so that variations in the price of gasoline can be compensated for as appears later. For the second purpose the pipe 15 has a connection at 17 with the three-way valve 13 so that continued operation of the pump after the valve position in Figure 7 has been assumed will only result in the return 70 of the gasoline to the underground tank.

75 80 Figure 4 is a view similar to Figure 2, illustrating the disposal of the parts prior to the dispensation of the liquid from the glass container,

85 Figure 5 is a detail sectional view illustrating the adjustment of the liquid level tube,

90 Figure 6 is a view similar to Figure 2, illustrating the disposal of the parts during the liquid dispensing operation,

95 Figure 7 is a sectional view of the discharge and inlet valves in the foregoing position,

100 Figure 8 is a detail view of the coin receiver taken substantially on the line 8-8 of Figure 1.

Assuming the valve plunger 5 to have been left pulled out (Figure 6) by a previous purchaser, a subsequent purchaser must first pull out on the initiating plunger 1 thereby returning the inlet and discharge valves 13 and 20 to the original position in Figures 2 and 3. The action is accomplished by the engagement of the heel 27 with the lug 26. The plunger 1 is slidably supported upon guides 28 in the casing.

After the required amount of gasoline has been pumped into the container 7 the purchaser inserts the coin C in a slot 29 in the casing. The coin is thus introduced 6 into what is generally known as the coin receiver. For the purpose of the present description the coin is assumed to be a silver dollar for which four gallons of gasoline may be purchased at 25¢ per gallon. 10 The tube 16 makes provision for variations in the price of gasoline, and both the function and construction are brought out more fully later.

The coin receiver comprises a slotted head 15 30 carried by an arm 31 which is pivotally mounted at 32. The arm has an extension 33 to which the weight 34 is adjustably attached, and a lever 35 to which the coin plunger 3 is connected. The extension 33 20 normally rests against the stop 36. The counterweight 34 keeps the coin receiver in the normal position in Figure 8, but upon a pull on the coin plunger 3 the receiver is moved to the dotted line position. The 25 coin receiver and the plunger 3 thereof occupy positions at right angles to the plungers 1, 4 and 5 of the remaining mechanism.

The spring 37 and pivoted lever 38, respectively situated at the ends of the slot 30 in the head 30 complete a pocket by which the coin is receivable. A spring 39 between the right end of the lever 38 and the arm 31 tends to rock the lever upon its pivot into the closing position. The coin C when inserted 35 into the pocket of the receiver, will be frictionally held by the spring 37 and lever 38, but a coin or slug smaller in diameter than the standard silver dollar will not be held but will roll out into the slug chute 40 which leads directly to the slug box 41. Upon movement of the coin receiver to the dotted line position, noted before, the inner end of the lever 38 engages the stop 36 thereby releasing pressure upon the coin C 45 and permitting it to drop into the coin chute 42. The coin chute stands at one side of the slug chute 40 (Fig. 8) but has a slug extension 86 which leads to the box 41 also. The coin chute has an offset 87 which leads 50 to the coin box 88.

A coin stop 43, operable across the extension 86 and normally in position thereacross as in Figure 2 stops the coin C in position in front of the cupped end 44 of 55 the rack 45. A pull upon the main plunger 4, which is the act next in order after inserting the coin and pulling the plunger 3, rocks a bell-crank 46 upon its pivot 47 so that the hook end 48 thereof presses against 60 the coin and thus against the cupped end 44 of the rack 45, resulting in the turning of the pinion 49 and lowering of a valve stop 50. The valve stop has a rack portion meshing with the pinion 49. The stop 65 is suitably guided at 51 so that it moves in

a rectilinear path. It is normally engageable by a latch 52 pivoted on the valve plunger 5 so that the valve plunger may not be pulled out prior to the proper time. The latch is held seated by a spring 85. The 70 displacement of the valve stop 50 permits pulling out of the valve plunger, and this act, as already stated, closes the inlet valve 13 to the upper part of the pipe 11 (Figs. 6 and 7) and opens the discharge valve 20 75 so that the gasoline may run out.

Motion of the main plunger 4 is transferred to the bell-crank 46 by means of a link 53 which is connected at the ends as shown. The collar 54 to which the lower 80 end is connected engages one end of the spring 55 mounted on the plunger 4 and bearing against the adjacent wall of the casing. This spring returns the plunger 4 when released, but the purchaser must hold the plunger 4 out until he has begun pulling upon the valve plunger 5, otherwise the valve stop 50 would return and prevent such pulling out of the plunger 5 by virtue of the reengagement of the stop 50 with the 85 latch 52.

A heel 56 on the main plunger 4 displaces the coin stop 43 by the engagement with a lug 57 on the coin stop when the plunger is pulled out as described. Both the plunger 95 and the coin stop have common support upon a bearing 58, and a spring 59 interposed between the lug 57 and the bearing serves to return the coin stop upon ultimate release of the main plunger 4. This release 100 of the plunger and consequent relaxation of pressure of the hook end 48 upon the coin permits the coin to fall from engagement with the cupped end 44 and to drop into the offset continuation 87 of the coin chute 105 42.

It is anticipated that an attempt might be made to effect the dispensation of gasoline by inserting a washer in the coin receiver. Assuming the attempt to have been made, 110 the washer will come to rest upon the coin stop 43 as does a legitimate coin, but upon pulling forwardly upon the plunger 4, the hook end 48 of the bell-crank 46 will simply pass through the hole in the washer and thereby avoid displacement of the valve stop 50, which it will be remembered, is a prerequisite to the operation of the valve plunger 5. Inasmuch as the hook end 48 has passed through the hole in the washer, 120 the washer will be hung up or suspended in space upon the displacement of the coin stop 43.

The forward pull of the plunger 4 rocks a pawl lever 61 upon its pivot 62. The confronting ends of the lug 57 and the pawl 61 are beveled so that the lug 57 rides past the pawl and takes up a position therebehind as in Figure 4 when the plunger 4 is pulled out. The release of the plunger 4 130

is not accompanied by the return of the coin stop 43 because the coin stop is now held, and the attendant retraction of the hook-end 48 will release the suspended washer which 5 now drops into the supplemental slug chute 86 and so into the box 41.

Release of the coin stop 43 is effected by engagement of a release lug 64 on the side of the valve plunger 5 with an arm 65 extending from the pawl lever 61. An outward pull of the valve plunger 5, and consequent engagement of the lug 64 with the arm 65, will rock the lever 61 upon its pivot and release the lug 57 so that the spring 59 15 may move the coin stop 43 back to its original position across the coin chute 42 and above the supplemental slug chute 86.

The hook end 48 of the bell-crank 46 operates in an aperture in a fixed plate 66 in 20 front of the cupped end 44. The conjunction of the chutes 42, 86, the cupped end 44, the plates 66 and 43 defines what may aptly be termed a coin chamber 67, because it is into the space thus roughly defined by the 25 parts mentioned that the coin drops for the subsequent action of the mechanism. The pawl lever 61 is counterweighted at 68, and the tendency of the counterweight is to hold the lever against a fixed stop 69.

30 Variations in the price of gasoline can be compensated for only by regulating the amount to be dispensed for a given sum of money. If the price per gallon increases the apparatus must be adjusted to dispense 35 less than four gallons for the one dollar standard herein adopted. If the price per gallon drops the apparatus must be adjusted to dispense more than four gallons for the one dollar standard. The foregoing price 40 variations are met by adjusting the tube 16, and the adjustments of the tube are made in reference to the major four gallon mark 70 on the container 7 (Fig. 1) and in reference to the supplemental marks 71 and 45 72, respectively above and below the main mark 70.

A pinion 73 (Fig. 5) meshes with a rack 74 on the side of the tube 16. The lower end of the tube is built with a circular skirt 75 50 in spaced relationship with the wall of the tube to thereby produce an annular recess 76 into which the sleeve 77 upon the upper extremity of the pipe 15 extends. The sleeve is fixed in position by a screw 78. A 55 packing 79 prevents leakage of gasoline at the slidble joint between the skirt 75 and sleeve 77. Similarly, a gland 80 prevents leakage of gasoline from the container 7 around the outside of the tube 16.

60 In practice, provision is made for access to the pinion 73 by an authorized person only. Such provision may include a door near the top of the standard or casing 6. Appropriate turning of the pinion 73 will raise 65 or lower the tube 16 in reference to the marks

on the outside of the container 7 so that more or less gasoline may be dispensed for a given price.

A spring 89 presses between the casing 6 and an extension 90 on the initiating plunger 1 to push the plunger inwardly when released. The extension carries a roller 91 which is engageable with the lever 92 of the pinion 49 upon the outward pull of the plunger 1 thereby to insure moving the cup 75 44 and stop 50 to the proper initial positions. The extremity of the plunger 1 terminates in a heel 93.

This heel is engageable with a pivoted arm 80 94 which upon outward movement of the plunger therefore swings to the dotted line position in Fig. 4 thus engaging the arm 65 and swinging the pawl lever 61 downward. This act disengages the coin stop 43 so that the stop may return to proper position in 85 front of the cupped end 44.

A sectional construction of the valve plunger 5 prevents repeating the dispensation of gasoline prior to the insertion of a coin for 90 the next purchase. The sections are designated 95 and 96 in order to distinguish them. The first of these has a pin 97 which rides in a slot 98 of the second. The plunger 5 may be pulled out (Fig. 6) to open the valve 20 (Fig. 7) for dispensation of the gasoline 95 but an inward push of the plunger with the intention of opening the valve 13 to the tank 7 is defeated by the riding of the section 96 relatively to the section 95. The latter remains fixed in place until the plunger 1 is 100 pulled out, and with that act the parts are so restored that only the insertion of another coin will make possible the further dispensation of gasoline.

The operation is readily understood and 105 inasmuch as the parts have been described the cycle of operation can be gone through in the order of the various steps.

The spring 89 pushes the initiating plunger 1 inwardly of the casing 6. It is therefore necessary to first pull upon the exposed part of the initiating plunger prior to the insertion of a coin C into the slot 29. This is necessary in order to move the section 95 of the valve plunger 5 over to the right of the 110 casing (Fig. 2), thereby opening the inlet valve 13 to the glass container or tank 7 and closing the discharge valve 20 (Fig. 3).

This act of the initiating plunger 1 (Fig. 120 2) also extends the stop 50 and insures the positioning of the cupped end 44 of the rack 45 in proper relationship to the coin chute 42 and to the coin chamber 67. The latch 52 assumes a position behind the extended stop 50 and prevents an outward pull of 125 the valve plunger 5.

Operation of the pump handle 2 will cause the elevation of gasoline from the underground tank (not shown) to the container 7 by way of the pipe 11 and the open inlet 130

valve 13. The purchaser should watch the rising level of gasoline in the container (Fig. 1) and stop when such level reaches the upper end of the tube 16. Should he continue 5 operation of the handle 2 the gasoline will simply overflow into the pipe 15 and thus return to the underground tank.

Insert silver dollar C in the slot 29 (Figs. 1 and 8), and pull the coin plunger 3 out. 10 Upon insertion in the slot 29 the coin is held between the spring 37 and the lever 38 of the coin receiver, and being of the required size will not roll out of the head 30. But a coin or slug of smaller size will 15 roll out upon pulling the plunger 3, and will fall into the chute 40 whence it passes into the box 41. The pull upon the plunger 3 now transfers the coin receiver from the full line position in Figure 8 to the dotted 20 line position, whereupon the engagement of the lever 38 with the stop 36 will compress the spring 39 and release the coin which then drops into the coin chute 42 and assumes a position in the coin chamber 67 as indicated by dotted lines in Figure 2.

The coin stop 43, being in position, supports the coin C as stated. The coin plunger 3 may now be released. The main plunger 4 is closed. This act rocks the bell-crank 30 46 so that the hook end 48 presses against the coin C and pushes the rack 45 to the right by virtue of the engagement of the coin with the cupped end 44 of the rack. The motion of the rack 45 turns the pinion 49 in the 35 counter-clockwise direction and displaces or lowers the valve stop 50. The same act of the plunger 4 displaces the coin stop 43 so that passage to the supplemental slug chute 86 is opened. But the coin has already been 40 moved to the full line position in Figure 4 and there is no possibility of the coin dropping in the chute 86. The pawl lever 61 holds the coin stop 43 in the displaced position by virtue of the engagement of the lug 45 57 behind the pawl.

A pull on the valve plunger 5 to the left is now in order. The valve stop 50 having been displaced from the path of the latch 52 (Fig. 4) permits such pull so that the 50 valve plunger 5 assumes the position in Figure 6. The action of the plunger 5 will turn the valves 13 and 20 from the positions in Figure 3 to the positions in Figure 7. The previously measured gasoline in the 55 container 7 will run out the now open valve 20. The valve 13 is closed to the upper part of the pipe 11, and should the purchaser continue operation of the pump handle 2 the gasoline passes into the lower part of 60 the pipe 11 and returns to the underground tank by way of the connection 17 (Fig. 7) and the common return pipe 15.

Return of the initiating plunger 1 to the starting position will be insured by the engagement of the lug 26 with the heel 27

should the spring 89 for any reason fail to function. The outward pull of the plunger 5 also brings the roller 64 into engagement with the arm 65 rocking the pawl 61 and releasing the coin stop 43 so that the latter 70 may assume the receiving position for the next coin. The same function is performed by the initiating plunger 1, which, upon being pulled out will cause rocking of the arm 94 by engagement of the heel 93 thereby to rock the pawl 61 (see dotted lines, Fig. 4) and release the stop 43.

Release of the main plunger 4 will result in a relaxation of the pressure of the hook end 48 against the coin (see Fig. 4). The coin is therefore free to drop into the coin chute 87 and into the coin box 88 beneath it. The release of the lug 57 from the pawl 61 permits the coin stop 43 to move back in readiness for the next coin and gasoline dispensing operation as already stated.

Should the purchaser insert a washer of the exact size of a silver dollar the action will be this: The washer will assume a position in the coin chamber 67 as in the case 90 of the coin C (Fig. 2). The subsequent pull upon the main plunger 4 will cause rocking of the bell crank 46, but the hook ends 48 will pass through the hole in the washer and thereby avoid movement of the latch 95 45 and consequent displacement of the valve stop 30.

An attempt to obtain gasoline by pulling upon the plunger 5 will be frustrated by the engagement of the latch 52 with the valve 100 stop (Fig. 2). The pull upon the plunger 4 will also displace the coin stop 43 as before, and the subsequent release of the plunger 4 and return of the bell-crank 46 will release the washer which then drops 105 into the supplemental slug chute 86.

The purpose and mode of adjustment of the tube 16 are readily understood from Figures 1 and 5. The price per gallon of gasoline often fluctuates so that the dollar 110 standard herein adopted will not agree if the price varies either above or below the 25¢ per gallon. The tube is therefore adjusted one way or the other in reference to the major four-gallon mark 70 (Fig. 1) so 115 that more than four gallons are dispensed if the price drops or less than four gallons if the price increases.

While the construction and arrangement of the improved vending apparatus is that 120 of a generally preferred form, obviously modifications and changes may be made without departing from the spirit of the invention or the scope of the claims.

I claim:—

1. Liquid vending apparatus comprising a container, a pump having a pipe for delivering liquid to the container, a container discharge pipe, connected inlet and discharge valves in the respective pipes, a 120

- liquid return pipe extending into the container and having connection with the delivering pipe at the inlet valve, and means for turning the inlet valve to positions of communication of the pump with the container or of the pump with said return pipe and correspondingly turning said discharge valve to positions of non-discharge or discharge in reference to the container.
- 10 2. Liquid vending apparatus comprising a container, a pump having a pipe delivering liquid into the container, a container discharge pipe, inlet and discharge valves in the respective pipes, a rod connecting the valve handles causing operation in unison, a liquid return pipe leading from the container having a connection joining the delivery pipe and the inlet valve thereof, means for operating the pump filling the container to the level of the return pipe, and means to turn the inlet valve either into position to deliver liquid to the container or to return the liquid to the return pipe by way of said connection and correspondingly 25 turn the discharge valve into positions of non-discharge or discharge, the latter position of the inlet valve preventing continued delivery of liquid to the container by said pump operating means.
- 30 3. Liquid vending apparatus comprising a container, a pump having a pipe for delivering liquid from the pump to the container, a three-way valve situated in said pipe, a return pipe leading from the container and having connection with the delivery pipe at said valve, and means for setting the valve either into position to deliver liquid from the pump to the container and cut out the return pipe connection or to 40 deliver liquid from the pump to the return pipe at said connection, said latter position of the valve preventing filling of the container beyond a predetermined level upon continued operation of the pump.
- 45 4. Liquid vending apparatus comprising a container, a pump having a pipe delivering into the container, a discharge pipe leading from the container, a valve in each pipe respectively in position to normally establish communication of the pump with the container and to close the discharge pipe, the handles of the valves being connected, means for manual actuation of the pump to fill the container to a predetermined level 50 as a preliminary step to the operation of the apparatus, a valve plunger for the reversal in position of the valves, and a coin-controlled mechanism permitting operation of said plunger for the purpose described.
- 55 60 5. Liquid vending apparatus comprising a container, a pump having a pipe delivering to the container, a container discharge pipe, a valve in each pipe respectively establishing communication of the pump with the container and closing the discharge pipe, the valve handles being connected, means for manually operating the pump to preliminarily fill the container to a predetermined level, a valve plunger for simultaneously closing the delivery pipe and opening the discharge pipe, a valve stop normally in position to prevent operation of said plunger, and coin-controlled mechanism for displacing the stop to permit operation of the plunger for the purpose described.
- 65 70 75 80 85 90 95 100 105 110 115 120 125 130 135
6. Liquid vending apparatus comprising a container, a pump having a pipe delivering to the container, a container discharge pipe, a valve in each pipe respectively establishing communication of the pump with the container and closing the discharge pipe, said valves having a bell-crank and arm respectively, a rod connecting the discharge valve arm and one arm of the bell-crank, a pin on the other arm of the bell-crank, a valve plunger having a finger with a slot receiving the pin, said plunger having a latch, a stop normally in position at one side of the latch, and means to displace the stop permitting passage of the latch and movement of the plunger for the reversal in position of the valves.
7. Liquid vending apparatus comprising a container, liquid inlet and discharge pipes, each having a valve respectively in the open and closed positions, a rod connecting the handles of the valves, a valve plunger for reversing the positions of the valves, said plunger having a latch, a stop in position to intercept said latch, said stop having a rack, a second rack, a main plunger having a bell-crank for shifting the second rack, means for delivering a coin in position between the bell-crank and second rack permitting said shifting, and a pinion connecting the two racks thereby displacing the stop permitting passage of the latch and operation of said plunger for the purpose described.
8. Liquid vending apparatus comprising a valve operating plunger having a latch, a rack having a stop normally in position to intercept the latch, a rack having a pinion meshing with said stop rack, a main plunger having a bell-crank with an end movable toward the rack, means for delivering a coin into position between said bell-crank end and the rack permitting motion of the rack and displacement of the rack stop upon operation of the main plunger, and means adjacent to said end of the rack to stop the coin in an engageable position.
9. Liquid vending apparatus comprising a valve-operating plunger, a latch on the plunger, a rack stop intercepting the latch, a rack having a pinion meshing with the rack stop, a bell-crank having a hook end confronting an end of the rack, a coin stop, a coin chute, a coin receiver for delivering a coin to the chute and into a resting position upon said coin stop, and a main plunger

having connection with the bell crank to actuate said hook-end against the coin, thereby to move the rack and displace the rack stop permitting passage of the latch 6 and operation of the valve plunger.

10. Liquid vending apparatus comprising a valve-operating plunger having a latch, a rack having a stop in position to intercept the latch, a rack having a pinion meshing 10 with the stop rack, said rack having a cupped end, a bell-crank having a hook end movable toward said cupped end, a chute for delivering a coin into position between said hook and cupped ends, a coin stop upon 15 which the coin rests in engaging position, a main plunger having a link connection with the bell-crank for rocking the bell-crank and shifting the racks to displace the rack stop, and a chute with which the coin 20 then comes into registration and into which the coin drops upon relaxation of pressure 25 on the main plunger.

11. Liquid vending apparatus comprising a valve-operating plunger having a latch, a 25 rack having a stop intercepting the latch, a rack having a pinion for displacing the rack thereby permitting passage of the latch stop, said rack having a cupped end, a bell-crank having a hook end movable toward the rack, 30 a slug chute, a coin stop in position over the slug chute, a coin chute for delivering a coin upon the stop in position between the hook and cupped ends, a main plunger for rocking the bell-crank and pressing the hook 35 end against a coin thereby shifting the rack, and means on the main plunger for displacing the coin stop thereby permitting the dropping of a washer into the slug chute if dropped into the coin chute in substitution 40 for a coin, the hook end of the bell-crank passing through the hole in the washer upon operation of the main plunger and preventing the required motion of the rack.

12. Liquid vending apparatus comprising 45 a valve-operating plunger having a latch, a rack having a stop intercepting the latch, a rack having a pinion for displacing the stop rack and having a cupped end, a slug chute, a coin stop in position over said chute and 50 having a lug, a bell-crank having a hook end movable toward the rack, a coin chute for delivering a coin in position upon the stop, a main plunger for rocking the bell-crank to press the hook end against the coin 55 and against the cupped end to move the rack, a heel on the main plunger engaging the coin-stop lug to displace the coin stop upon operation of the main plunger, and means to hold the coin stop in displaced 60 position thereby uncovering the slug chute to receive a washer if substituted for a coin, the hook end of the bell-crank passing through the hole in the washer in the event of said substitution and passing into said

cupped end preventing said motion of the 65 rack.

13. Liquid vending apparatus comprising a valve-operating plunger, means normally holding the plunger from operation, a coin chute, means for releasing the valve plunger 70 upon delivery of a coin to a predetermined place by said chute, a coin receiver comprising a pivoted arm having a lever, a head on the arm having a spring-actuated lever for receiving said coin, a plunger in connection 75 with the lever for turning the arm and head into a discharging position over the coin chute, and a stop then engageable by the pivoted lever to depress the spring thereof and release the coin. 80

14. Liquid vending apparatus having a coin receiver comprising a pivoted arm, a coin chute, a head on the arm for delivering a coin to said chute, a slug chute, a spring in fixed position upon the head, and a 85 spring-pressed pivoted lever on the opposite side of the head to cooperate with the spring in gripping a coin prior to the foregoing delivery, said spring and pivoted lever holding a coin of given size but permitting a 90 coin of smaller size to roll out into the slug chute during transit of the head to delivering position over the coin chute.

15. Liquid vending apparatus comprising a container, liquid inlet and discharge pipes 95 connected with the container, a valve in each of the pipes being in open and closed positions respectively, means connecting the valves for simultaneous operation, and a valve plunger for reversing the positions of 100 the valves, said plunger being made in sections causing one section to remain stationary after said reversal of the valve regardless of the manipulation of the remaining section. 105

16. Liquid vending apparatus comprising a container, liquid inlet and discharge pipes connected with the container, a valve in each pipe respectively in the open and closed positions, a rod connecting the handles of the 110 valves for simultaneous operation, a valve plunger comprising a section having connection with one of the valve handles and having a pin, and a second plunger section having a slot receiving said pin, said pin and 115 slot connection permitting operation of the plunger to reverse the position of the valves but preventing return of the valves to the original position.

17. Liquid vending apparatus comprising 120 a container, liquid inlet and discharge pipes connected with the container, a valve in each pipe respectively in the open and closed positions, a rod connecting the handles of the valves for simultaneous operation, a 125 valve plunger comprising a section having connection with one of the valve handles and having a pin, a second plunger section hav-

- ing a slot receiving said pin, said pin and slot connection permitting operation of the plunger to reverse the position of the valves but preventing return of the valves to the 5 original position, and means engageable with the valve plunger for returning the plunger and said valves to the original positions.
18. Liquid vending apparatus comprising 10 a container, liquid inlet and discharge pipes connected with the container, a valve in each of the pipes respectively in the open and closed positions, means connecting the handles of the valves insuring simultaneous operation, a valve plunger composed of two sections, one being connected with one of the valve handles and having a lug, said sections being in pin and slot connection permitting simultaneous movement of both sections upon a pull on the plunger in one direction to reverse the position of the valves but permitting movement of only one of the sections upon reverse operation of the plunger, and an initiating plunger having a 20 heel engageable with said lug to reversely move the valve plunger to restore the valves to the original positions.
19. Liquid vending apparatus comprising 25 a valve operating plunger having a latch, a rack having a stop normally in position to intercept the latch and prevent movement of the plunger, a rack having a pinion meshing with said stop rack, a main plunger having a bell crank with an end movable toward the rack, means for delivering a coin into position between said bell-crank end and the rack permitting motion of the rack and displacement of the rack stop upon operation of the main plunger, a coin stop normally 35 in position to support the coin prior to operation of the main plunger, and means actuated by the main plunger upon the foregoing operation thereof to displace the coin stop.
20. Liquid vending apparatus comprising 45 a valve operating plunger having a latch, a rack having a stop normally in position to intercept the latch and prevent movement of the plunger, a rack having a pinion meshing with said stop rack, a main plunger having a bell-crank with an end movable toward the rack, means for delivering a coin into 50 position between said bell-crank end and the rack permitting motion of the rack and displacement of the rack stop upon operation of the main plunger, a coin stop normally 55 in position to support the coin prior to operation of the main plunger, means actuated by the main plunger upon the foregoing operation thereof to displace the coin stop, 60 means including a pawl acting to hold the coin stop in the displaced position, and subsequently operated means including a pivoted arm for rocking the pawl to release the coin stop permitting the stop to assume 65 the original position.
21. Liquid vending apparatus comprising 70 a container, a pipe having connection thereto and with a course of supply for delivering liquid to the container, a container discharge pipe, connected inlet and discharge valves in the respective pipes, an open surplus liquid return pipe adjustably projecting upwardly into the container variably to determine the height and quantity of liquid 75 which may be discharged therefrom, and means for turning the inlet valve to positions of communication or non-communication of the liquid supply with the container and for coincidently turning the discharge 80 valve to positions of non-discharge and discharge with reference to the container.

NEPHI W. CLAYTON.
